CLAIM

The ornamental design for a lacrosse stick head, as shown and described.

DESCRIPTION

FIG. 1 shows a perspective view of my claimed design. FIG. 2 shows a further perspective view of my claimed design.

FIG. 3 shows a right side view of my claimed design.

FIG. 4 shows a left side view of my claimed design.

FIG. 5 shows a first end view looking distally from the proximal end of my claimed design.

FIG. 6 shows a second end view looking proximally from the distal end of my claimed design.

FIG. 7 shows a top view of my claimed design; and,

FIG. 8 shows a bottom view of my claimed design.
